UNITED STATES PATENT OFFICE.

HARRY E. COOMBS, OF KINGSTON, NEW YORK.

GAME.

SPECIFICATION forming part of Letters Patent No. 621,960, dated March 28, 1899.

Application filed December 10, 1897. Serial No. 661,377. (No model.)

To all whom it may concern:

Be it known that I, HARRY E. COOMBS, a citizen of the United States, residing at Kingston, in the county of Ulster and State of New York, have invented a new and original Game called "Mitrelude," of which the following is a specification, reference being had to the accompanying drawings.

The invention consists of a board with edge flanges having a raised surface with a recess in the center thereof and a series of elongated projections arranged a distance from the central depression adapted to form rebounding-surfaces.

15 The invention is illustrated in the accompanying drawings, in which—

Figure 1 is a plan view of the board; Fig. 2, a sectional view of the same on the line A B of Fig. 1. Fig. 3 is a detailed sectional view showing one of the projections. Figs. 4 and 5 show a form of shooter which may be used in the game. Figs. 6 and 7 are views of a disk which may be used in the game.

The board, which is of preferably rectangular form and is provided with a surrounding flange, (indicated by letters,) has a raised central portion, in the center of which is a recess

1. Extending from the raised surface of the board at a distance from the central recess are a series of elongated projections 2, 3, 4, and 5, which form rebounding-surfaces, as will be hereinafter described. Four of these projections are used, and they are set alternately at right angles to each other. Disks

35 6 or the like are used in playing the game, and they are shot against one of the projections by means of a shooter similar to that shown in Figs. 4 and 5, or by a fillip movement of the finger at such an inclination in

40 relation to one of the projections that they will rebound therefrom and enter the recess

1. By placing the projections at different an-

gles or along different lines in relation to the recess 1 the number of positions from which the disk may be shot to strike one of the projections at such an angle that the rebound will send it in or in the direction of the recess is increased.

45 The projections are not intended to act as guards to the recess to prevent a disk or the like shot directly at the same from reaching its destination, but only as rebounding-surfaces.

The shooter illustrated herein comprises a cylinder *a* and a piston *b* for striking the disks 55 guided therein provided with an enlarged head, which is normally held pressed against the end of the cylinder by an elastic cord *c*.

I claim—

1. The combination with a game-board having edge flanges and a central raised portion with a recess therein, of a series of elongated projecting surfaces arranged a distance from said recess to leave a space between the same and the projections for the movements of the 60 playing-disks, said projections extending in a tangential direction in relation to said recess, said projections being adapted to act as rebounding-surfaces.

2. The combination with a game-board having edge flanges and a central raised portion with a recess therein of a series of elongated projections extending from said raised portion, each projection being arranged at right angles to the contiguous projections with its 65 central portion opposite the end of one of said contiguous projections and its end opposite the central portion of the other contiguous projection, substantially as described.

HARRY E. COOMBS.

In presence of—

DE WITT ROOSA,
WILBUR L. HALE.
